PAUL A. BANCEL, OF MONTCLAIR, NEW JERSEY, ASSIGNOR TO INGERSOLL-RAND COMPANY, OF JERSEY CITY, NEW JERSEY, A CORPORATION OF NEW JERSEY

SURFACE CONDENSER

Application filed September 29, 1928. Serial No. 309,171.

This invention relates to surface condensers, and more particularly to that type of surface condenser which comprises a plurality of surface cooling tubes extending longitudinally through a chamber across the path of the steam flow.

In a single pass condenser of this nature having water tubes over which steam to be condensed passes, the tubes are cooler at the inlet portions than at their outlet portions because in passing through the tubes, the cooling water is warmed from the heat absorbed, and in condensing the steam the water temperature rises progressively along the length of the tubes in the direction of water flow. The effect of this temperature condition is to decrease the capacity of the water tubes to condense steam in the sections of the condenser which are relatively remote from the water inlet.

It is the object of the present invention to arrange the tubes within a condenser so that the steam will naturally apportion itself along the length of the condenser so as to produce substantially the same depth of penetration throughout, or in other words, to utilize the entire available cooling surface of the condenser in the most efficient and practical manner. A still further object of the invention is to produce a condenser which is extremely simple in its construction and which depends solely upon the arrangement and location of the various tubes for effecting equal depth of penetration of steam.

It has been proposed heretofore to direct steam in larger quantities toward the cooler end of the condenser by an arrangement in which the tubes converge toward the warmer end, thereby increasing the frictional pressure drop from steam inlet to air outlet gradually in the direction of the warmer end of the condenser. In such an arrangement however, the tube sheet for the outlet water box is substantially smaller than that at the cooler end and the outer shell is also contracted at the warmer end. This results in a condenser having its weight disposed eccentrically and presents structural difficulties.

It is an object of this invention to enable the tubes to be arranged convergent toward

the warmer end of the condenser and permit the condenser shell, outlet water box and tube sheet to be of similar size at both ends. In the preferred embodiment of the invention the tubes are divided into groups in each of which the tubes converge. The space between the tube groups is occupied by filler pieces. An advantage of this construction is that the size of the filler pieces may be changed in various parts of the condenser so as to provide steam lanes whereby the flow of steam may likewise be changed as desired. Another advantage of the invention is that the tubes of condensers at present in use may be rearranged to provide improved longitudinal distribution of the steam.

Other objects and advantages will be in part obvious and in part pointed out hereinafter.

In the accompanying sheet of drawings, like characters of reference are employed to designate like parts throughout; and,

Figure 1 is a sectional view taken on a horizontal plane through the condenser looking in the direction of steam flow.

Figure 2 is a sectional view taken on the line 2-2 of Figure 1; and,

Figure 3 is a sectional view taken substantially along the line 3-3 of Figure 1.

Referring now to the drawings, the condenser consists of an outer shell 10 of any conventional type having steam inlet 11 and outlet 12 for the withdrawal of condensate and uncondensable gases. The shell 10, is of any suitable length and is traversed by a plurality of tubes 13, supplied with water from the water head 14 which has an inlet 15, the said tubes discharging into a head 16, having an outlet 17 at the opposite end of the condenser. A tube sheet 18 closes one end of the water head 14 and a sheet 19 of the same size closes an end of the water head 16 and these two plates serve to support the tubes in position within the condenser and prevent leakage of the circulating water into the shell 10.

In this particular instance, the tubes 13 within the condenser are arranged so that at one end the center to center distance d is greater than the center to center distance e

at the other end to effect equal depth of penetration. The gradual crowding of the tubes toward the warmer end of the condenser restricts the steam flow more in the 5 warmer end and tends to produce a correspondingly greater pressure drop in the steam flow at that end than at the cooler end. Accordingly, since in this instance, the pressure drops through all parts of the condenser 10 are equal, the steam velocity and quantity is greater at the cooler end where the condensing capacity is greatest. In order to distribute the tubes at this end as equally as possible over the tube sheet 19, a plurality 15 of fillers 20, 21 and 22, may be arranged longitudinally of the tubes 13 so as to divide certain groups of tubes from each other. These fillers are wedge shaped, and preferably are hollow closed boxes, having their 20 diverging walls parallel to the steam flow. The walls of the fillers diverge in the direction of the water outlet box 16 so as to substantially fill the space between the tube groups. These fillers are secured to the plates 25 18 and 19 in any suitable manner as by means of bolts 23.

While these fillers may be arranged in any suitable manner, it is preferable to arrange them as shown in Figure 3 on account of the 30 extreme compactness obtained by this arrangement of parts. If desired a greater or lesser number of fillers may be used. However, irrespective of these details in manufacturing, the essential features of the invention 35 are always preserved.

The steam pressure is uniform at the inlet 11. This pressure, which is a partial vacuum, is maintained by a suitable evacuating apparatus (not shown) which may with- 40 draw condensate and uncondensable gases from the outlet 12.

In a condenser correctly built in accordance with the practice of this invention, the fillers 20, 21 and 22 fill substantially all of 45 the space between the tube groups. An advantage of the use of fillers is that the space between the fillers and the tubes may be changed to provide lanes by which the steam path restriction may be varied to suit con- 50 ditions. If it is found that the restriction at the warmer end is too great, fillers narrower at the broad end may be inserted.

It is obvious that I have provided a condenser which is extremely simple in its construction. Convenience of arrangement of parts, compactness, lightness and comparative strength are further desiderata that have been borne in mind in the production and development of this invention.

60 I claim:

1. A condenser having tubes with different temperatures along their length resulting in unequal capacities for condensing steam, there being fillers between certain of said 65 tubes to divide the same into groups, the

tubes in each group converging towards each other in the direction of the region of highest circulating water temperature.

2. A condenser having a shell of substantially uniform cross section throughout its 70 length and tubes in said shell with different temperatures along their length resulting in unequal capacities for condensing steam, there being fillers between certain of said tubes to divide the same into groups, the 75 tubes in each group converging towards each other in the direction of the region of highest circulating water temperature.

3. A condenser having tubes with different temperatures along their length resulting in unequal capacities for condensing steam, there being wedge shaped fillers between certain of said tubes to divide the same into groups the tubes in each group converging towards each other in the direction of the region of highest circulating water temperature. 80

4. A condenser having a shell of substantially uniform cross section throughout its 90 length and tubes in said shell with different temperatures along their length resulting in unequal capacities for condensing steam, there being wedge shaped fillers between certain of said tubes to divide the same into groups the tubes in each group converging towards each other in the direction of the 95 region of highest circulating water temperature.

In testimony whereof I have signed this specification.
